UNITED STATES PATENT OFFICE.

KONRAD MALCHER, OF GLEIWITZ, GERMANY.

DUMPING-CAR.

1,370,658.

Specification of Letters Patent.

Patented Mar. 8, 1921.

Application filed July 5, 1917. Serial No. 173,860.

To all whom it may concern:

Be it known that I, KONRAD MALCHER, a subject of the King of Prussia, German Emperor, and resident of Teucherstrasse, Gleiwitz, Upper Silesia, Germany, have invented new and useful Improvements in Dumping-Cars, of which the following is a specification.

In some classes of railway cars the bottom 10 consists of a central, longitudinal, fixed portion and two side parts hinged to the said central part and capable of being thrown back to meet with their outer edges above the central part and thus form inclined surfaces 15 over which the contents of the car may slide out of the same and fall down at both sides of the track.

According to the present invention the upper flange of the girders is attached to the 20 fixed section of the car bottom and the web extends slantingly outwardly, the lower flange extending substantially horizontally outwardly, so that, when the movable parts of the bottom are opened upwardly, the webs 25 of the girders form a prolongation of the slanting surface of the upturned bottom parts along which the contents of the car slide out on to the rails. The web may also be curved in cross section. One advantage 30 of the construction, is that the bottom of the car may be mounted more closely over the top of the rails or track.

The girders may be rolled or they may be composite, *i. e.* the parts may be riveted together.

In order to render the present specification easily intelligible, reference is had to the accompanying drawing, in which similar reference letters denote similar parts 40 throughout the several views:

Figure 1 is a vertical longitudinal section through the car;

Fig. 2 a similar part section through one side drawn on an enlarged scale;

Figs. 3 and 4 are similar part sections of modified forms of the invention.

The fixed part *b* of the car bottom is supported on the upper flange of the longitudinally disposed girders *a*, the webs of which are slanted outwardly. The angle formed 50 between the web and the lower flange *c* may be filled out with wood or other suitable material as at *d* to form one continuous sliding surface for the car load, when the bottom door has been thrown back. The inclined surface may be prolonged by means of an outwardly downwardly inclined plate *f*.

As illustrated at Fig. 4 a girder of *E*-shaped cross-section may be employed, the web *a* slanting outwardly.

I claim as my invention:—

1. In a dumping car the combination of a longitudinal fixed bottom portion and lateral movable portions hinged to the said fixed portion, girders mounted substantially 65 at the edges of said fixed portion and having their webs slanting downwardly and outwardly, the angle between the lower flange and the web being filled out to form an uninterrupted inclined plane with the web. 70

2. In a dumping car the combination of a longitudinal fixed bottom portion and lateral movable portions hinged to the said fixed portion, girders mounted substantially 75 at the edges of said fixed portion and having their webs slanting downwardly and outwardly, the angle between the lower flange and the web being filled out to form an uninterrupted inclined plane with the web, and an outwardly inclined plate *f* attached to the lower flange of the girder to 80 form a continuation of a sliding surface.

In testimony whereof I have affixed my signature in the presence of two witnesses.

KONRAD MALCHER.
